UNITED STATES PATENT OFFICE.

RICHARD F. DOWNEY, OF MILWAUKEE, WISCONSIN, ASSIGNOR TO HUGO LOEWENBACH,
OF MILWAUKEE, WISCONSIN.

FOLDING-MACHINE.

1,246,403.

Specification of Letters Patent. Patented Nov. 13, 1917.

Application filed February 16, 1915. Serial No. 8,553.

To all whom it may concern:

Be it known that I, RICHARD F. DOWNEY, a citizen of the United States, and resident of Milwaukee, in the county of Milwaukee and State of Wisconsin, have invented certain new and useful Improvements in Folding-Machines; and I do hereby declare that the following is a full, clear, and exact description thereof.

10 My invention has for its object to provide a simple, effective and accurate sheet-folding machine, adapted more particularly for folding sheets of paper for insertion in envelopes being so constructed and arranged 15 that a circular mandrel is adapted to grip one corner of a sheet and coil the same in the form of a hollow tube, which tube projects from the mandrel, there being means for supporting and guiding the outer end of 20 said tube coincident to its formation. Thereafter means is provided for releasing the guide means and first flattening and thereafter introducing the flattened free end of the tube into a creasing mechanism through 25 which the tube is drawn to provide longitudinal folds throughout the length of the tube and thus transversely crease the sheet of paper to permit its insertion in an envelop. The construction and arrangement 30 also embodies, under certain conditions, means for bending the hollow tube intermediate of its ends prior to the same being introduced into the creasing mechanism, whereby a transverse fold of the end of the tube 35 is also effected. Thus it will be seen that the paper may be folded by the above operation to fit within an envelop, and the invention further contemplates a selective control of the transverse tube folding means to pro- 40 vide for envelopes of differing lengths.

With the above and other objects in view the invention consists in certain peculiarities of construction and combination of parts as set forth hereinafter with reference to the 45 accompanying drawings and subsequently claimed.

In the drawings—

Figure 1 represents a longitudinal sectional view of a folding machine embodying the features of my invention, the section being indicated by line 1—1 of Fig. 3; 50 Fig. 2, a cross-section of the same, the section being indicated by line 2—2 of Fig.

3 and the creasing rollers being removed to more clearly show the actuating means 5; therefor;

Fig. 3, a plan view of the folding machine with parts broken away and in section to show details of construction more clearly;

Fig. 4, a longitudinal sectional view of 60 the machine taken upon a plane as indicated by line 4—4 of Fig. 3;

Figs. 5 and 6, enlarged detail sectional views showing the marginal mandrel and its associated mechanism in its starting and finishing positions;

Fig. 7, a detailed sectional view illustrating the mandrel actuating rack and its connections, the section being indicated by line 7—7 of Fig. 1;

Figs. 8 to 12 inclusive illustrate diagrammatic views of the various steps in the operation of the machine to fold a sheet completely, and

Fig. 13, a perspective view of the folded 75 sheet.

Referring by characters to the drawings, 1, 1', 1'' and 1''' represent the side and end walls respectively of a rectangular frame, the side wall 1 of which carries a stud 2 for the reception of a revoluble circular mandrel 3, the same being formed with a guide flange 3' having a circular margin-receiving rim 3''. The web portion of the circular mandrel is provided with a hub 4' that is revoluble upon the stud and this hub also carries a toothed pinion 4 adapted to mesh with the teeth of a rack-bar 5 that is slidably mounted in bearings formed in the side-wall 1. The outer end of the rack-bar terminates with an abrupt shoulder 5', which shoulder engages an actuating lever 6, the same being intermittently coupled to the rack-bar by a lip of a yieldable stop-dog 7, which stop-dog is secured to the rack-bar 95 and has a nose 7' that is adapted to engage lock and release tappets 8 and 8' respectively, which form part of a plate 8'' that is preferably adjustably secured to the frame-wall 1.

The actuating lever 6 is rigidly mounted upon a transversely disposed rock-shaft 9, which shaft is mounted in bearings that project from the side walls of the frame. This oscillatory drive-shaft also carries a beveled gear-wheel 10 that meshes with a beveled 105 gear-wheel 11.

pinion 10' which is secured to a longitudinally disposed cam-shaft 11, the same being journaled in bearings that are affixed to the side wall 1 and end wall 1" of the frame. 5 The cams 11', 11", are mounted upon the cam-shaft 11 for engagement with side rails 12 of a sheet-supporting and tucking basket, the said rails being pivoted to the frame side wall 1, straddling the mandrel and in 10 parallel relation to its axis.

The sheet-receiving rim 3" of the mandrel carries a spring-controlled gripping tongue 13, which tongue is normally adapted to press downwardly upon the face of the rim. 15 The gripping tongue 13 is provided with a tappet pin 14 projecting rearwardly therefrom for engagement with a cam-jaw 15 that projects from the rack-bar 5, the said cam-jaw being so positioned that when the 20 tongue is in a vertical plane relative to the mandrel axis, it is lifted in opposition to its spring resistance, whereby a receiving throat is formed between the opposite faces of the tongue and mandrel rim for the 25 reception of a corner of the sheet to be folded. The cam jaw is also provided with a stop-shoulder 16 which engages the tappet pin 14 to prevent overthrow or further rotation of the mandrel in its clockwise recovery movement, whereby the parts are held 30 in proper sheet-receiving positions. The mandrel, in this exemplification of my invention, is predeterminedly arranged to make approximately one and a half turns 35 forming the flat sheet into a hollow tube and thereafter the mandrel comes to rest. In order to release the gripping engagement 40 of the sheet by the gripping tongue 13 after the same has come to rest, I provide a cam-controlled release-shoe 17, the position of 45 which shoe is normally above the path of travel of the tongue tappet-pin 14, but is moved downward at the proper time with relation to rotation of the mandrel, whereby it engages the tappet-pin and lifts the 50 tongue clear of the face of the mandrel-rim, thus releasing the tube. In order to effect a time movement of the release-shoe 17, the same is mounted upon a reciprocative rock- 55 arm 17', which rock-arm is pivoted to the side wall of the frame and normally holds the release shoe in an idle position by means of a spring 17". The rock-arm is engaged by a cam 18, which is secured to the oscillatory drive-shaft 9.

In order to effect a tight roll of the sheet margin upon the mandrel rim, I provide a presser-foot 19, which, as shown, is secured to the rear wall 1" of the frame and is 60 adapted to yieldingly engage the paper as it is coiled about the rim thereunder and, to limit the movement of the actuating lever 6 on its forward or idle stroke, I provide a buffer-pin 20, the said actuating arm being 65 limited on its working stroke by engage-

ment with a socket that is formed in the frame.

The side bars 12 of the basket are connected at their outer ends by a tucker-bar 21, which tucker-bar is in the form of a 70 taut wire strand connected to upwardly extended arms of a yoke 21', the same being pivotally suspended between the rails. The preponderance of weight of the yoke is positioned below the pivot-point thereof, whereby 75 the tucker-bar strand is held by gravity in a vertical direction with respect to its point of oscillation. The side rails of the basket are also braced by a saddle 22, which performs the function of a stripper in connection with the tucker-bar when the basket is elevated at its outer end. Projecting upwardly between the basket rails are a pair 80 of circular guide binders 23, 23', which binders together form a part of a circle for 85 the support and guidance of the outer end of the sheet when it is wound in tube form. These guide binders are provided with ear extensions which are connected by springs 23", whereby said binders are drawn together to form their normal circular contour. Cam-arms 24 project from the guide-binders for engagement with the side rails of the basket, whereby the guide-binders are 90 spread apart when the basket is elevated. 95 The said guide binders 23, 23' are pivotally mounted upon a stud 24', which projects from one wall of the frame. Thus the guide binders are rendered expandible and contractible and are positioned in approximately 100 axial alignment with the mandrel and spaced therefrom.

A skeleton frame including end plate portions 25^a and connecting bars 25^b is secured to the rear wall 1" of the main frame by 105 integral connection of one of the plate portions with the wall to project over the main frame and above a table 26, which table is secured to the upper portion of said main frame. Arbors 27' of creasing rolls 27 are 110 journaled in the frame 25 and the engaging faces of these creasing rolls are positioned over the tucker-bar 21, whereby said tucker-bar, when lifted, is caused to pass between the engaging surfaces of the rolls. The 115 creasing rolls carry pinions 28 which are engaged by the opposite toothed surfaces of a rack-bar 29, whereby motion is imparted to the rolls. The rack-bar is obliquely disposed with relation to the rolls and is suitably supported in a guide-block 25^c that projects from the base of the roll-carrying frame. One end of the roll-actuating rack-bar is connected by a strap 29', the opposite 120 end of which strap is secured to a crank-arm 30 that is carried by the cam-shaft 11. The table is provided with one edge in alignment with the rim of the mandrel, which edge carries an upturned guide flange 26', whereby a marginal edge of a sheet to 130

be folded is guided to the mandrel. The opposite edge of the table carries an adjustable gage-strip 31 for the purpose of guiding the juxtaposed edge of the sheet 5 to be folded and the adjustable feature is for the purpose of accommodating different widths of sheets.

In operation, a sheet A is disposed upon the table between the guide flange and gage-strip, and is fed forward to a position under the gripping tongue of the mandrel, its upper edge being alined parallel with the axis of the mandrel due to its engagement with a gage-lip 23'', which forms an extension of the guide-binder 23', the said extension being above the plane of the table. The actuating lever 6 is now started upon its working stroke, as indicated by the arrow, whereby motion is imparted to the mandrel through its gear connection with the actuating arm. At the start of rotation of the mandrel, the gripping tongue tappet-pin 14 is released from its engagement with the cam-jaw 15, whereby the corner of the paper is clamped to said mandrel. Further movement of the actuating lever 6 will cause the mandrel to rotate approximately one and a half turns and the upper edge of the sheet, which is initially engaged 25 by the guide-binder arm 23', will follow the rotary movement of the mandrel, whereby said sheet is formed into a tube that is lapped approximately one-half turn. At the completion of this rotary movement of 30 the mandrel it will be observed that the nose 7' of the stop-dog 7 will engage the release tappet 8', whereby said stop-dog is forced backwardly to be freed from its coupling union with the actuating lever. Hence 35 there will be no further movement of the mandrel and the gripping tongue thereof will come to rest at approximately a point diametrically opposite that of its starting point. After the actuating lever is released 40 from the rack-bar 5, further movement of said lever will first cause the cam-controlled rocker-arm 17' to move downwardly, whereby the release shoe will come into the path of travel of the tappet-pin 14 to thus cause 45 the marginal corner of the coiled sheet to be disengaged from the mandrel rim. Further movement of the actuating lever 6 will cause the cams 11' of the cam-shaft 11 to engage the side rails of the basket, whereby 50 the same will rise. Coincident to this rise, it will be observed that the arms 24 of the guide-binders 23, 23', will be contracted by the side rails, whereby said guide-binder arms are spread apart or opened to permit 55 the unsupported portion of the tubular sheet to be stripped from its forming position with relation to the mandrel. Thus the outer end of the tube is gradually raised and the tucker-bar which engages said tube 60 intermediate of its ends will flatten out the

tube formation of the sheet as the latter comes in contact with the creasing rolls. Upon completion of the upward movement of the basket, the tucker-bar will crease the flattened and transversely folded sheet 70 intermediate of its ends and force the same at its creased point between the rolls, the said bar being forced between said rolls to a point above their contact faces, together with the now longitudinally creased sheet. 75 Coincident to this movement the gear connection of the creasing rolls with the cam-shaft 11 will cause said rolls to rotate, whereby the sheet, which is now folded transversely and longitudinally, will be so firmly creased and fed outwardly from between the rolls to a position accessible to the operator. Thus the creasing operation is completed.

It is obvious that, in some instances, the device may be arranged to crease sheets of different sizes by, for example, substituting different sized circular mandrels, under which conditions the lock and release tappets 8 and 8' can be adjusted to trip the rack-bar 5 sooner or later in the cycle of operation. It is also apparent that the creasing mechanism may be moved toward or away from the mandrel for varying the point of the longitudinal crease of the sheet 95 and it is also obvious that, in some instances, where narrow paper is used, the longitudinal creasing mechanism may be dispensed with, in which instance the extreme end of the tube would be caused to travel straight 100 through the creasing rolls in place of, as shown, being folded back upon itself before the creasing operation.

It is also apparent that, upon the idle stroke of the actuating lever, said lever will 105 engage the shouldered end of the rack-bar 5 and cause the same to move in a recovery direction to impart rotation to the mandrel and, as the rack-bar travels in this recovery stroke the back face of the stop-dog 7 will 110 engage the locking tappet 8, whereby the nose of said locking dog will be forced outwardly in the path of travel of the actuating lever to automatically couple the same to the rack-bar, whereby upon the working stroke 115 of the aforesaid lever the rack-bar is again manipulated.

I claim:

1. A sheet folding machine comprising a mandrel having a sheet-engaging rim adapted to receive one end of a sheet to be coiled thereon, means carried by the mandrel for grippingly engaging the edge of a sheet, means for imparting rotation to the mandrel whereby a sheet is coiled thereon in the form 125 of a hollow tube, means for guiding the other end of the sheet during its tube formation, said guiding means being releasable upon completion of the tube forming movement of the mandrel, a creasing means positioned 130

- adjacent the said other end of the sheet and means for feeding the said outer end of the coiled sheet to the creasing means.
2. A sheet-folding machine comprising a mandrel having a margin-receiving rim, means for introducing a marginal edge of a sheet to the rim, means carried by the rim for engagement with the marginal edge, means for imparting rotation to the mandrel, whereby a sheet is coiled in the form of a hollow tube, means for guiding the outer end of the hollow tube during its formation, a vertically movable tucker-bar normally positioned under the hollow tube formed by the mandrel and intermediate of its ends, creasing rolls above the hollow tube in alignment with the tucker-bar, and actuating mechanism for the tucker-bar whereby the same is caused to flatten the tubular formed sheet against the creasing-rolls and to cause said tucker-bar to move between said rolls, whereby the flattened tube is fed through the aforesaid rolls to crease the same both in a transverse and longitudinal direction.
3. A folding machine comprising a revolute mandrel having a sheet-engaging marginal rim, a spring-controlled tongue adapted to engage the rim whereby a sheet to be folded is gripped, an actuating gear mechanism for the mandrel, an oscillatory lever, means for automatically coupling and uncoupling the gear actuating means in connection with the lever, a pivotal basket projecting outwardly from a position adjacent the face of the mandrel, cam-actuating means for the basket in gear connection with the actuating lever, expandible and contractible guiding binders in approximate alignment with the mandrel, means associated with the basket for controlling movement of the guiding binders, a pair of engaged intermittently rotative creasing rolls positioned above and outwardly of the face of the mandrel and spaced therefrom, a tucker-bar carried by the basket in alignment with the engaging faces of the rolls, and means for raising the tongue in opposition to its spring tension.
4. A folding machine comprising a rotary mandrel having a sheet margin receiving rim, a spring-controlled gripping finger carried by the mandrel for engagement with its rim, a pinion carried by said mandrel, a rack-bar engageable with the pinion, a stop-dog carried by the said rack bar, an oscillatory actuating lever, tappet lock and release means for effecting release and lock of the stop-dog with the actuating lever, a cam-

jaw for actuating the gripping finger when the same is moved to a sheet-receiving position, a cam-shoe for actuating the finger when the mandrel has completed a rotatory movement, cam means associated with the actuating handle for operating the cam-shoe, a cam-controlled tucker-bar, means for moving the same across the axial line of the mandrel, and driven creaser rolls positioned above and outwardly of the mandrel associated with the tucker-bar.

5. A folding machine comprising a rotary mandrel having a sheet margin receiving rim, a spring-controlled gripping finger carried by the mandrel for engagement with its rim, a pinion carried by said mandrel, a rack-bar engageable with the pinion, a stop-dog carried by said rack bar, an oscillatory actuating lever, tappet lock and release means for effecting release and lock of the stop-dog with the actuating lever; a cam-jaw for actuating the gripping finger when the same is moved to a sheet-receiving position, a cam-shoe for actuating the finger when the mandrel has completed a rotatory movement, cam means associated with the actuating handle for operating the cam-shoe, a cam-controlled tucker-bar, means for moving the same across the axial line of the mandrel, driven creaser rolls positioned above and outwardly of the mandrel associated with the tucker-bar, a pair of circular expandible and contractible guide binders positioned forwardly of said mandrel and approximately in axial alignment therewith, and means associated with the movable tucker-bar for actuating the same.

6. A sheet folding machine comprising a mandrel having a sheet engaging rim adapted to receive one end of the sheet to be coiled thereon, means carried by the mandrel for grippingly engaging the corner edge of a sheet, means for imparting rotation to the mandrel whereby the sheet is coiled thereon in the form of a hollow tube, creasing means positioned intermediate of the ends of the coiled sheet, and means for flattening and bending the coiled sheet at the intermediate point and for delivering the same to the creasing means.

In testimony that I claim the foregoing I have hereunto set my hand at Milwaukee, in the county of Milwaukee and State of Wisconsin, in the presence of two witnesses,

RICHARD F. DOWNEY.

Witnesses:

N. E. OLIPHANT,
M. E. DOWNEY.
